UNITED STATES PATENT OFFICE.

GOMER W. PRICE, OF SAN FRANCISCO, CALIFORNIA.

CENTRIFUGAL PUMP.

1,072,650.

Specification of Letters Patent. Patented Sept. 9, 1913.

Application filed October 20, 1909, Serial No. 523,672. Renewed February 24, 1913. Serial No. 750,417.

To all whom it may concern:

Be it known that I, GOMER W. PRICE, a citizen of the United States, residing in the city and county of San Francisco and State of California, have invented certain new and useful Improvements in Centrifugal Pumps, of which the following is a specification.

My invention relates to the class of centrifugal pumps, and while applicable to all such pumps in which end-thrust exists, due to difference in pressure on opposite sides of the impeller or runner, it is particularly intended for centrifugal pumps of the inclosed-15 impeller type in which such end-thrust is experienced to a greater extent.

The object of my invention is to overcome this end-thrust; and to this end my invention consists in the novel construction and 20 arrangement of parts which I shall herein-after fully describe, by reference to the accompanying drawings in which—

Figure 1 is a vertical section of my improved centrifugal pump, showing one form 25 of specific construction of the two sides or walls of the throat of the collection chamber. Fig. 2 is a sectional detail of the collection chamber showing another constructive form of the throat sides, the impeller 30 being shown as affected by pressure on its suction side to cause it to move to afford relief by opening a passage to the clearance space on the opposite side. Fig. 3 is a sectional detail of the same parts of Fig. 2, but 35 showing the opposite movement of the impeller and the consequent relief on the other side.

The pump here shown is one in which the impeller is mounted to rotate in a vertical 40 plane on a horizontal axis, but it may be one in which a mounting at right angles is had, that is, with the impeller shaft vertical.

1 is a bed, in the standards 2 of which are suitable bearings 3 in which is journaled the 45 impeller shaft 4 in such manner as to have a slight longitudinal movement.

5 is the casing or shell and 6 is its peripheral collection chamber, having a suitable discharge not here shown.

50 7 is the impeller or runner mounted on shaft 4, and 8 is the suction inlet in the shell into the eye of the impeller.

9 are the clearance spaces between the faces of the impeller and shell on opposite 55 sides, and 10 are passages in the rear side of the impeller which permit any water

which may collect there, especially under pressure, to go through the impeller into the collection chamber.

11 are packing rings to form joints between the necks 12 of the impeller hub and the flanges 13 of the shell faces. These packing rings or joints may be of any suitable character tending to prevent leakage. They are here indicated as those of the Patent No. 834,848, granted Oct. 30, 1906, upon my application, their function being to prevent or to tend to prevent the water from escaping from the two sides of the impeller, or from the clearance spaces into the passages 10 or into the suction inlet 8.

14 is a side plate in the shell which permits of the introduction of the impeller.

15 are annular projections in the two sides of the throat 16 of the collection chamber 6. In some cases, as in Fig. 1, these projections are formed as rings, say of steel, separate from the casing and are inserted in place. In other cases, as in Figs. 2 and 3, the projections are integral parts of the casing. The adjacent faces of these throat projections are parallel plane surfaces, the distance between said faces being equal to the distance between opposite walls of the impeller blades. Their outer faces are chamfered or beveled down to an edge as shown.

The periphery of the impeller is turned perfectly round, true and smooth, the disks being finished of uniform thickness. The peripheries of the impeller disks just reach 90 and touch the edges of the throat projections 15.

The efficiency and reliability of a well designed and well built centrifugal pump are due in great part to the prevention of 95 water by-passing from the collection chamber to the suction inlet, and to overcoming the end-thrust of the impeller, due to these leakages. Much success in this line has heretofore followed the provision and use 100 of the packing rings 11, tending to make non-leakage joints; and if there were no leakages through these joints, the impeller would run in perfect hydraulic balance. But inasmuch as it is absolutely impossible 105 to maintain a joint without some leakage, the leakage on the two sides of the impeller are never alike, and there always exists an end-thrust toward the side or end that leaks the greatest quantity.

110 The purpose and effect of my present improvement will now be clearly appreciated.

2

First—it avoids excessive pressure in the clearance spaces each side of the impeller, by decreasing leakage. The pressure in these spaces is directly due and equal to the discharge or pressure head less what slight reduction may be suffered by the friction of the impeller disk on the inner surface of the water in said clearance spaces. The decrease of leakage into the clearance spaces is effected by my present improvement by the annular throat-projections 15 coacting with the peripheral surfaces of the impeller disks. The water at this point has little or no pressure, as all the energy given to it has here been converted into velocity, and, when properly confined, exerts but slight pressure in any direction other than radial; hence, when so confined, there is but slight tendency to flow in any other direction, the result being that when the pump is in operation, the pressure in the two clearance spaces is considerably less than that due to the discharge or pressure head. Second—if, due to a variation of pressure between the two sides of the impeller, or in the case of a pump having a vertical shaft with the weight of the moving parts to care for, the impeller is caused to move out of its central position shown in Fig. 1 to a position on one side as in Fig. 2, or on the other side as in Fig. 3, a passage will be opened to one or the other clearance space, between one of the throat projections 15 and the periphery of one of the impeller disks, through which, as shown by the arrows, a sufficient amount of water will be admitted to the proper side of the impeller to bring it back into alignment

again. The impeller is thus balanced, with but little loss of water or loss of horse-power, and the construction is very durable. The total end play of the impeller and shaft in extreme conditions which would cause the impeller to travel from one side to the other is slight.

Having thus described my invention what is claimed as new and desired to be protected by Letters Patent is:—

In a centrifugal pump, the combination of a shell having a peripheral collection chamber with an annular throat opening 50 into said shell, said throat having annular recesses in its side walls, and detachable relatively flat annular plates fitting into said recessed walls and having flared edges projecting inwardly beyond the walls of the throat, means for removably securing said plates in position, an impeller in the shell having the walls of its peripheral delivery extended to run against the peripheral surfaces of the side plate projections to form a joint tending to prevent leakage between them, the outer wall of said shell being removable whereby to obtain access to the interior of the shell and collection chamber, and said detachable wall having a flange 55 constituting in effect a part of one wall of the said throat.

In testimony whereof I have signed my name to this specification in the presence of two subscribing witnesses.

GOMER W. PRICE.
